(57) **CLAIM**

The ornamental design for a housing for an air conditioner as shown and described.

DESCRIPTION

FIG. 1 is a first perspective view of a housing for an air conditioner showing our new design.

FIG. 2 is a second perspective view thereof;

FIG. 3 is a front view thereof;

FIG. 4 is a rear view thereof;

FIG. 5 is a first side view thereof;

FIG. 6 is a second side view thereof; and,

FIG. 7 is a top view thereof.

The broken lines in the drawings show portions of the housing for an air conditioner that form no part of the claimed design.
